BOW-FACING OAR

Peter Schenk, Ketchikan, Territory of Alaska, assignor of one-third to Fred F. Nimitz, Ketchikan, First District, Territory of Alaska

Application September 22, 1934, Serial No. 745,148

9 Claims. (Cl. 9—25)

The present invention relates broadly to rowing apparatus and more particularly to devices of this character designed to enable an oarsman to face toward the bow of the boat while rowing.

5 The primary object of the invention is to provide a divided or bow-facing oar of improved construction which may be very easily applied and removed from operative relation to the boat, and in which there are no separable parts to become lost or misplaced when the oar is removed from the boat.

10 A further object resides in the novel and sturdy form of pivotal mounting for the oar whereby sufficiently large bearing surfaces are provided such as will not wear readily and permit wobbling of the oar after comparatively little use.

15 A further object is to provide a bow-facing oar which will be practically noiseless in operation, thus making the device particularly well adapted for use in hunting and fishing, as well as at any occasion where noise from the rowing is objectionable.

20 A still further object is to provide a device 25 of this character wherein friction is reduced to a minimum.

A still further object resides in the novel pivotal mounting arrangement whereby the oar will have a limited tilting movement when released.

25 Other objects and advantages will be apparent from the following detailed description, taken in connection with the accompanying drawings forming a part of this specification and in which drawings:—

30 Figure 1 is a view in side elevation of the oar shown applied to the gunwale of a boat.

35 Figure 2 is an enlarged longitudinal section through the oar shown applied to the boat.

Figure 3 is a top plan view showing portions 40 broken away for illustrating certain details of construction.

45 Figure 4 is a transverse section on the line 4—4 of Figure 3.

Figure 5 is a top plan view of the pivotal 50 mounting for the oar.

Figure 6 is a transverse section on the line 55 6—6 of Figure 5.

Figure 7 is a plan view of one of the bearing discs.

50 Figure 8 is an enlarged fragmentary detail section through the anti-friction bearing means.

Referring to the drawings in detail and wherein similar reference characters designate corresponding parts throughout the several 55 views, the device comprises an oar proper em-

bodying a blade section A and a handle section B pivotally joined together by the coupling device C having detachable pivotal mounting upon the mounting member or support D.

Referring first to the specific construction of 5 the mounting member or support D, the same embodies an elongated preferably flat base or attaching plate 5 provided with suitably spaced apertures 6 adapted to receive suitable screws or other fastening elements 7 whereby the 10 mounting member may be secured longitudinally of the upper edge of the side or gunwale 8 of the boat. Projecting upwardly from one end of the base plate 5 is an end plate 9 having a flat inner face arranged at a right angle to the 15 base plate. Extending longitudinally of the base plate 5 midway between the side edges of the plate is a cylindrical rock shaft 10 having an integral web 11 extended along its lower side and spacing the shaft above the base plate as 20 clearly shown in Figures 2 and 6. This rock shaft 10 extends from the end plate 9 to a point closely adjacent the opposite end of the base plate and is provided adjacent its free end with a transverse slot 12 which opens at the upper 25 side of the shaft as shown in Figure 6. Pivoted 30 mounted along one edge portion of the base plate 5 in transverse alignment with the slot 12 is a keeper 13 adapted to be swung into the slot 12 and provide means for retaining the coupling 35 device C in operative relation upon the mounting member. The keeper 13 is notched out as at 13' and the web 11 is received in this notch when the keeper is closed over the rock shaft. As will be observed in Figures 2 and 6, the web 35 11 is of a thickness less than the diameter of the rock shaft.

Referring now to the coupling device C, the same embodies a pair of elongated, spaced apart plates providing an upper or cover plate 14 40 and a lower or pivot plate 15 having rounded ends as shown in Figure 3. Projecting upwardly from the lower plate 15 at spaced points along its longitudinal center line, are two pivot studs 16 which project through the upper plate 14 45 and have threaded upper ends for receiving suitable nuts 17.

Pivotedly mounted upon each of the studs 16 is a segmental gear 18 formed of fiber or some such analogous material and having their teeth 50 in intermeshing engagement. Each of the gears 18 is provided with a flat extension 19. The segmental gears 18 are mounted between the plates 14 and 15 by anti-friction means allowing ready and easy pivoting of the gears and of a construc- 55

tion eliminating wear upon the preferably fiber gears. Extended axially through each gear 18 is a bearing sleeve 20 for engaging the pivot studs and preventing wear upon the gears. Arranged over each face of the gears is a bearing disc 21 having a diameter slightly less than the teeth of the gears. Encircling each pivot stud 16 at the confronting faces of each of the plates 14 and 15, are bearing discs 22, one of these bearing discs 22 being provided for each of the bearing discs 21. Arranged between companion sets of bearing discs 21 and 22 is a ball retaining disc 24 in which is mounted a number of ball bearings 25 to have rolling contact with the bearing discs. The ball bearings 25 have a diameter slightly greater than the thickness of the retaining disc and may be retained in the openings 26 in the disc in any preferred manner such as by prick punching or otherwise upsetting the metal slightly at the ends of the openings. Each retaining disc is provided with two concentrically arranged groups of ball bearings as shown in Figure 3, and each of the bearing discs 21 and 22 are preferably provided with annular raceways 27 in which the ball bearings rotate. This provision of the raceways 27 also assists in resisting relative lateral shifting of the bearing discs and reduces wearing strain upon the sleeve 20. It may here be well to state that the bearing discs 21 rotate with their respective gears 18.

Extending transversely across the under side of the lower plate 13 midway between the ends thereof, is a bearing extension 30 having a length equal to the width of the lower plate and having its sides rounded off into the under face of the lower plate as at 31. This bearing extension 30 is provided with a bearing groove or socket 32 opening at the lower side of the bearing extension and extending from end to end thereof. This elongated bearing groove 32 is slightly greater than semi-circular shape in cross section and provides a pair of stop flanges 33 along the open side of the groove which coact with the web 11 to limit rocking movement of the oar. The bearing groove 32 is of a size to have a bearing fit upon the rock shaft 10 and the bearing extension 30 is of such length that when placed upon the rock shaft, one end face of the extension will engage against the end plate 9 while the opposite end of the extension will engage upon the inner face of the keeper 13 so that the plate 9 and keeper 13 act to limit shifting of the coupling device C on the mounting member D.

Secured to the extension 19 of each segmental gear 18 is a longitudinally divided socket providing an attaching section 35 and a clamping section 36. The socket sections 35 and 36 have semi-circular-shaped body portions provided with apertured ears 37 adapted to receive suitable clamping screws or bolts 38 whereby the sections may be clamped about the oar sections A and B. The inner end of each attaching section 35 is formed with an end wall 40 which abuts against the flat outer end of the extension 19. A flange 41 extends at a right angle from the straight edge of the end wall 40 and is secured to the extension 19 by suitable rivets or the like 42. This manner of securing the socket to the extension of the segmental gears with a substantially butt joint provides a rigid coupling and will allow for the socket sections to be formed of a lighter material.

When placing the oar in operative relation to the boat, it is merely necessary to swing the

keeper 13 to an open position as shown in Figure 6 and then the oar may be slid laterally so that the rock shaft 10 is received in the bearing groove or socket 32. The oar is slid along the shaft 10 until one end of the bearing extension 30 engages the end plate 9 and after which the keeper 13 may be swung to its closed position in the slot 12 so that the oar is retained in position on the mounting member D. When the oar is so positioned on the mounting member, the oar is free to rock vertically but the coupling device C is held against swinging in a horizontal plane by the elongated rock shaft 10. When desiring to detach the oar from the mounting member, it is merely necessary to swing the keeper 13 open and then slide the oar off of the rock shaft. The stop flanges 33 not only limit rocking movement of the oar but also prevent the oar from being lifted off of the rock shaft. 20

By having the elongated bearing between the coupling device C and mounting member D, a sufficiently large bearing surface is provided such as will not wear quickly and cause wobbling of the oar. By having the gears 18 formed of fiber 25 or some such analogous material, the device will be practically noiseless in operation thus rendering the device particularly well adapted for use when hunting or fishing. Use of the fiber gears is made possible through the provision of the 30 novel mounting arrangement for the gears eliminating all wear upon the gears during operation.

Changes in details may be made to the form of invention herein shown and described, without departing from the spirit of the invention or 35 the scope of the following claims.

What is claimed is:

1. In a bow-facing oar, the combination of a supporting member provided with an elongated rock shaft, a coupling device embodying intermeshing gear segments each provided with oar section securing means, slidably fitting with an interlocking rocking connection on the rock shaft, and keeper means for releasably retaining the coupling device in position on the rock 45 shaft. 40

2. In a bow-facing oar, the combination of a supporting member having an elongated rock shaft on its upper side, a blade and handle coupling device having an elongated open ended bearing groove on its under side for slidably fitting on the rock shaft from one end of the shaft, a flange along each side of the bearing groove for retaining the coupling device against lateral movement off the shaft and limiting 55 rocking movement of the coupling device on the shaft, and releasable retaining means for retaining the coupling device against movement longitudinally off of the shaft. 50

3. In a bow-facing oar, the combination of a supporting member comprising a base plate having an upstanding end plate at one end thereof, a rock shaft extending from the end plate in spaced relation above the base plate, an oar coupling section having a grooved bearing extension 65 slidably fitting on the rock shaft with an interlocking engagement, and releasable keeper means on the supporting member and coacting with said end plate for retaining the coupling section rockably mounted on the supporting member. 70

4. In a bow-facing oar, the combination of a supporting member comprising an elongated base plate for attachment longitudinally of the gunwale of the boat, an upstanding abutment at one end of the base plate, a rock shaft ex- 75

tending longitudinally of the base plate from said abutment, a web extending along the lower side of the rock shaft, an oar section coupling device having a bearing groove for slidably fitting on the rock shaft from one end thereof and provided along each side of the groove with flanges engageable with said web for limiting rocking movement of the coupling device, and a keeper at the opposite end of the rock shaft from 5 said abutment for retaining the coupling device against longitudinal movement off of the rock shaft.

5. In a bow-facing oar, the combination of a supporting member comprising an elongated base plate having an upstanding end wall at one end thereof, a rock shaft extending longitudinally of the base plate from said end wall, a web connecting the rock shaft and base plate, an oar section coupling device having a bearing groove 10 in its lower side for slidably fitting on the rock shaft from one end thereof and providing flanges engageable with said web for limiting rocking movement of the coupling device, and a keeper pivoted on the base plate and having interlocking engagement with the rock shaft for retaining the coupling device against longitudinal movement off of the rock shaft.

6. In a bow-facing oar, the combination of a supporting member having an elongated rock shaft provided thereon, and an oar structure 15 having a bearing portion provided with an elongated open ended bearing groove having an interlocking sliding connection on the rock shaft.

7. In a bow-facing oar, a coupling section having a pair of intermeshing gear segments each formed with a flat extension having a straight outer edge, and an oar section socket for each segment, each embodying an attaching section having a flat end wall abutting said straight outer edge and a flange secured to said extension, and a clamping section coacting with the attaching section for clamping an oar section therebetween.

8. In a rowing device, a supporting member for attachment to the gunwale of a boat and provided with an elongated rock shaft, and an oar having a bearing extension provided with an elongated open ended bearing groove slidably receiving the rock shaft and permitting limited rocking movement of the oar on the shaft.

9. In a rowing device, a supporting member 20 for attachment to the gunwale of a boat and provided with an elongated rock shaft, and an oar having a bearing extension provided with an elongated open ended bearing groove slidably receiving the rock shaft and permitting limited 25 rocking movement of the oar on the shaft and means carried by the supporting member and coacting with the rock shaft for retaining the oar against movement longitudinally of the rock shaft.
